UNITED STATES PATENT OFFICE.

LA FAYETTE WILDERMUTH, OF COLUMBUS, OHIO.

GRASS-RECEPTACLE.

No. 836,230.

Specification of Letters Patent.

Patented Nov. 20, 1906.

Application filed May 12, 1906. Serial No. 316,568.

To all whom it may concern:

Be it known that I, LA FAYETTE WILDERMUTH, a citizen of the United States, residing at Columbus, in the county of Franklin 5 and State of Ohio, have invented a new and useful Grass-Receptacle, of which the following is a specification.

This invention relates to grass-receptacles for lawn-mowers of that general class shown in United States Letters Patent granted to me on the 17th day of November, 1903, under No. 744,657.

One object of the invention is to improve, simplify, and cheapen the construction of the receptacle and to reinforce and strengthen the bottom of the same by providing a vertical guide-flange which also serves as a guard to prevent the grass from clogging or otherwise obstructing the bearing-roller of the 20 mowing-machine.

A further object of the invention is to provide means for limiting the spreading movement of the sectional bottom and means whereby the receptacle may be supported at 25 any desired distance from the lawn-mower.

A still further object of the invention is to generally improve this class of devices, so as to add to their utility and durability as well as to reduce the cost of manufacture.

With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a 40 part of this specification, Figure 1 is a perspective view of a grass-receptacle constructed in accordance with my invention, showing the same in position on a lawn-mower. Fig. 2 is a bottom plan view of the receptacle detached. Fig. 3 is a longitudinal sectional view taken on the line 3-3 of Fig. 2. Fig. 4 is a detail side elevation of a portion of the frame and connecting-link. Fig. 5 is a perspective view of a portion of the bottom of the receptacle.

Similar numerals of reference indicate corresponding parts in all of the figures of the drawings.

The improved receptacle consists of a relatively stationary lower section 5 and a movable upper section 8. The upper section 6 is

preferably formed of a single piece of wire, an intermediate portion of which is bent to form a rear bar 7, and the ends of the wire extended forwardly and downwardly to form 60 side bars 8. The side bars 8 are bent at 9 to form vertically-disposed arms 10, the latter being coiled to produce eyes 11 and the ends of the wire extended laterally to produce terminal horizontally-disposed eyes or loops 12. 65 The bottom frame or section is substantially rectangular in shape, as shown, and provided with laterally-extending arms 13, the ends of which are supported in parallel relation with each other by means of a tubular member 14. Secured in any suitable manner to the lower frame are a plurality of overlapping plates 15 and 16, which constitute the bottom of the receptacle and are free to move 70 laterally, so that the device may be readily adjusted to accommodate machines of different sizes. The ends of the arms 13 are provided with lateral extensions 17, adapted to engage the ends of the tubular bar 14, 80 thereby to limit the expansible movement of the overlapping bottom sections, and thus prevent said sections from becoming separated. The lower frame is reinforced and strengthened by a longitudinally-disposed rod 85 18, one end of which is secured to the rear bar 19 of the lower frame, while its opposite end is twisted or otherwise coiled around the tubular member 14, as shown. The forward ends of the plates 15 and 16 are extended a short distance beyond the arms 13 90 and bent to form terminal flanges 19', the ends of one of the plates or sections being bent downwardly to form a guiding-groove 20, adapted to receive the flange of the adjacent plate or section. By having the sections or plates formed in the manner described the bottom of the receptacle is not only materially reinforced and strengthened by the terminal flange, but the latter forms 100 a guard and serves to prevent the grass from sliding off the movable sections and clogging or otherwise obstructing the bearing-roller of the mowing-machine.

Attention is called to the fact that the 105 arms 13 of the lower frame extend transversely beneath the free edges of the plates or sections so as to form a support for the same, while the flexible member 14 serves as an additional support for the bottom plates and also serves to maintain the arms in proper position.

As a means for attaching the receptacle to the mowing-machine there are provided suitable coupling members, preferably in the form of hooks 21, adapted to engage the eyes 12, 5 said hooks being formed with elongated slots or openings 22, adapted to receive the bolts which serve to hold the bearing-roller in position. It will thus be seen that by releasing the bolt 23 the slotted ends of the hooks may 10 be adjusted longitudinally, thereby to vary the distance between the roller and the adjacent end of the grass-receptacle, while by exerting a lateral pull on the side members of the lower frame the bottom sections or plates 15 may be extended laterally to adapt the receptacle to machines of different widths. The upper frame is pivotally mounted on the arms 13 and is provided with a hook 24, adapted to engage the handle 25 of the 20 mower when the receptacle is attached to the latter. The upper and lower frames are connected by a fabric covering 26, which forms the side and end of the receptacle, said fabric being folded and stitched at its lower edges 25 around the different parts of the frame to which it is attached.

The coupling members are permanently attached to the mower by the bolts 23, and when it is desired to use the receptacle the 30 latter is attached to the mower by positioning the eyes 12 over the hooks 21, as best shown in Fig. 4, after which the upper frame is elevated and supported in such position by passing the end of the hook 24 over the adjacent portion of the handle. In order to remove the receptacle, it is merely necessary to lift the eyes 12 out of engagement with the hooks when the receptacle may be disconnected from the machine and compactly folded, 35 so as to take up very little room when not in use.

From the foregoing description it is thought that the construction and operation of the devices will be readily understood by 45 those skilled in the art, and further description thereof is deemed unnecessary.

Having thus described the invention, what is claimed is—

1. In a device of the class described, a receptacle including a frame, a plurality of laterally-movable overlapping sections secured to the frame and forming the bottom of the receptacle, arms carried by the frame and extended beneath the sections, a tubular member embracing the arms, and means carried by the arms and adapted to engage the tubular member for limiting the expansible movement of said sections.

2. In a device of the class described, a receptacle including a frame, a plurality of laterally-movable overlapping sections secured to the frame and forming the bottom of the

receptacle, said sections being provided with a terminal flange, arms carried by the frame and extended beneath the sections at said 65 flange, a tubular member embracing the arms, and means carried by the arms and adapted to engage the tubular member for limiting the lateral movement of said sections.

3. In a device of the class described, a receptacle including a frame, a plurality of laterally-movable overlapping sections secured to the frame and forming the bottom of the receptacle, a guiding-groove formed in the 75 end of one section, a flange formed on the adjacent section and adapted to engage said groove, arms carried by the frame and extended beneath the sections, a tubular member embracing the arms, and means carried 80 by the arms and adapted to engage said member for limiting the lateral movement of the sections.

4. In a device of the class described, a receptacle including a frame, a plurality of laterally-movable overlapping sections secured to the frame and forming the bottom of the receptacle, arms carried by the frame and extended beneath the sections, and a tubular member embracing the arms, said arms being 90 provided with terminal extensions adapted to engage the tubular member for limiting the expansible movement of said sections.

5. In a device of the class described, a receptacle including a frame, a plurality of laterally-movable overlapping sections secured to the frame and having one end of each thereof projected beyond said frame, arms extended beneath the projected ends of the sections, a flexible member embracing the 100 arms, and means carried by the arms and adapted to engage the flexible member for limiting the lateral movement of said sections.

6. In a device of the class described, a receptacle including a frame, a plurality of movable overlapping sections secured to the frame and forming the bottom of the receptacle, one end of each section being extended beyond the frame and bent upwardly to 105 form a vertically-disposed flange, arms extending transversely beneath the extended ends of the movable sections, a coiled spring embracing the arms, and lateral extensions on said arms adapted to engage the adjacent 110 ends of the spring for limiting the lateral movement of said sections.

In testimonny that I claim the foregoing as my own I have hereto affixed my signature in the presence of two witnesses.

LA FAYETTE WILDERMUTH.
